UNITED STATES PATENT OFFICE.

SERGE DE PROCOUDINE-GORSKY, OF GRANSTAD, KONNERUD, NEAR DRAMMEN,
NORWAY.

APPARATUS FOR THE PRODUCTION OF COLORED CINEMATOGRAPHIC FILMS.

1,412,089.

Specification of Letters Patent. Patented Apr. 11, 1922.

Application filed September 20, 1919. Serial No. 325,265.

To all whom it may concern:

Be it known that I, SERGE DE PROCOUDINE-GORSKY, a Russian subject, residing at present at Granstad, Konnerud, near Drammen, Norway, have invented certain new and useful Improvements in Apparatus for the Production of Colored Cinematographic Films; and I do hereby declare the following to be a full, clear, and exact description 10 of the invention, such as will enable others skilled in the art to which it appertains to make and use the same, reference being had to the accompanying drawings, and to letters or figures of reference marked thereon, 15 which form a part of this specification.

The apparatus proposed enables the production of a positive total picture in natural colors by the successive copying of three successive part-pictures taken on a negative ribbon through three different light-filters as usual in the three-color system. According to this invention all those part-pictures which have been taken by means of a certain light-filter (for instance all the "red" 20 part-pictures) are copied on the positive ribbon, the first time both ribbons pass through the apparatus. When the ribbons pass through the machine the second time, the same positive ribbon receives part-pictures of another category (for instance the "green" ones) and finally the third time part-pictures of the third category—the "violet" ones—are copied. It is evident that in order to enable this, the ribbons must be 25 drawn through the machine step by step, it being also necessary to give the negative ribbon a speed three times as great as that of the positive ribbon, in order that every third part-picture of the negative ribbon 30 may be copied on the picture-surfaces of the positive ribbon in the order they follow after each other. The copying is effected by lighting the films pressed together at the moment when they are brought to a standstill. When the films are at a standstill 35 after each forward motion, they are pressed together, lighted, and are again loosened from each other, all these operations being done with the necessary speed. After having been drawn forward to the necessary 40 extent, the films are again brought to a standstill, pressed together, lighted, and so on.

The operation begins with the placing of

a certain part-picture of the negative ribbon on the picture-surfaces of the positive ribbon, then both ribbons are moved forward step by step, in such a way that the steps are carried out in the same time, but with a speed so chosen that each step of the negative ribbon is thrice as long as that of the positive ribbon. When the ribbons pass through the machines for the first time, all uniform part-pictures in the negative ribbon for instance all "red" ones are copied. When this is done the negative ribbon is 55 moved on to an extent corresponding to that of the picture of the positive ribbon. Next time the ribbons pass through the machine, part-pictures of the second category, for instance the "green" ones, are copied on the 60 same positive ribbon, and then the ribbon is moved on another step in order that the part-pictures of the third category may be copied thereon. To enable the surfaces of the negative and positive pictures to coincide exactly during the lighting step both 65 ribbons are engaged by retaining devices, common to both of them, after each displacement. After lighting, the ribbons are again automatically removed from each 70 other and loosened from the retaining devices, thereby avoiding damage to the emulsified surfaces of the films consequent upon 75 accidental contact when they are shifted.

The annexed drawings show by way of 80 example a form of construction of the apparatus proposed. Fig. 1 is a view of the apparatus partly in side elevation and partly in central vertical section, and Fig. 2 is a 85 view partly in front elevation and partly in vertical section on the line A—B, Fig. 1.

The base 1 has a pin 2, to which a frame 46 is fixed, the central portion of this frame forming a housing for the gearing, which is tightly covered by a cap. In the back 90 part of the frame a journal 3 is arranged which carries a pulley 5 driven from a motor (not shown) arranged on the base by a suitable connecting element 4. From this pulley motion is transferred to the shaft 8 95 (Fig. 1) by means of the toothed gears 6, 7. A disc 8^a fitted with two toothed rings 16, 20 is keyed to the inner end of the shaft 8. A toothed wheel 15 which is fixed to a shaft 12 located above shaft 8 meshes with the 100 toothed ring 16 and another toothed wheel 9

in the form of a Maltese cross meshes with ring 20, the Maltese cross gear 9 being connected with a crown gear 10 by means of a sleeve 11 which is loose on shaft 12. The latter is journaled in bearings 13 and 14 mounted in the frame, and has fastened to it adjacent the bearing 13 a sleeve 61 which carries a second crown gear 17 and an eccentric 18. The sleeve 61 is formed with a spiral cam track 19 against which a roller provided on the free end of an arm 60 mounted on shaft 59 yieldingly presses, with the result that shaft 59 is caused to rock or turn about its axis when the shaft 12 rotates. This is utilized in the manner below described. The driving gears 23 and 22 respectively (Figs. 1 and 2) on the shafts 24 and 25 (Fig. 2) mesh with and are driven by the crown gears 10 and 17, said shafts also carrying gears 26 and 27 which mesh with gears attached to drums 28 and 29, the gearing being so proportioned that the angular velocity of the drum 29 is three times as slow as that of the drum 28. The mechanism just described is of duplex character; that is to say, there are at each side of the machine a pair of drums 28 and 29 and associated gears and, hence, a pair of shafts 24 and 25 and associated gears, as will be understood from Fig. 2 in which all four drums are shown. The negative ribbon N, indicated at 30, is led over the four drums 29, 28, 28 and 29 and passes the lighting device 31 between the drums 28 (Figs. 1 and 2). The latter consists of an electric lamp 33 and an optical condenser 32. The power of the light may be regulated by means of a movable partition wall 34 which may be replaced by a light-filter of the desired color. Between the light-source 33 and the condenser 32 a rotating disc 35 is arranged which is provided with an opening for the purpose of effecting the exposure, which latter is interrupted when the films are moved forward. The shaft 36 of this disc is driven from shaft 8 at a constant angular velocity by means of the pairs of intermeshing gears 38 and 37.

In the form of construction shown, the rotating motion is transferred to the drums 28 from shaft 12 by means of the gears 10, 23 and 26 and the Maltese cross 9, i. e., with interruptions and step by step, while the drums 29 are rotated from said shaft 12 without interruptions by means of the gears 17, 22 and 27, the angular velocity of these two drums being three times slower however than that of the two drums 28. When as shown, the toothed wheels 15 and 16 have the same diameter, the drums 28 will rotate through 270° for each complete rotation of the shaft 8 (each rotation of shaft 8 causing a displacement of the Maltese cross 9 of 90°). Owing to this arrangement the negative film-ribbon 30 is consequently moved

forward at each step a distance equal to that of three picture-surfaces, provided that the circumference of the drums 28 is equal to the length of four picture-surfaces. The drums 29 make in the same time simultaneously a rotation of 270° and symmetrically shift the length of ribbon, which has been collected in the form of a loop C when the drum 28 has been at a stand-still. On the opposite side of the machine exactly the same operation, but in the opposite direction, takes place.

The positive film-ribbon P, indicated at 39, is arranged over the negative ribbon 30 and is moved forward by means of the pairs of drums 40 and 41, one pair being disposed at each side of the machine by the side of the corresponding drums 28 and 29. The drums 40 and 41 are connected with the drums 28 and 29 by means of the pairs of gears 42, 43 and 44, 45, respectively, but they rotate at an angular velocity which is one-third that of drums 28 and 29. The positive ribbon is moved forward in synchronism with the negative ribbon, but in such a way that during the time in which the negative ribbon is moved forward three lengths of a picture-surface, the positive ribbon is moved forward one length only.

The wheel gearing above referred to is as already mentioned arranged in a central casing in the frame 46. The lower part of this casing forms an oil reservoir 49 through which the ring gear 20 moves, said reservoir having a tap hole 51. The toothed wheels 10 and 17 run in an oil bath 50 with a tap hole 52. The shaft 12 is provided with an oil lubricator 53 while the disc 5 and the toothed wheel gearings 6, 7 are lubricated by means of the lubricator 54.

The shade of the lamp 33 is provided with three openings 55 (Fig. 1) fitted with corresponding light-filters which may be closed by means of elastic caps 56.

As the back-lash of the gearings might cause inconveniences owing to inaccuracy in the position of the two ribbons 30 and 39 in relation to each other, care has been taken to avoid this by attaching centering discs 57 to the drums 28. These discs are formed with four notches spaced 90° apart, which are engageable by the pointed ends of a pair of arms 58 fixed to the previously mentioned shaft 59, the motion being effected by rocking of said shaft due to the action of its arm 60 which is pressed against the cam track 19 on sleeve 61 by means of the spring 62 (Fig. 2). Each time the ribbons are moved forward the ends of the arms 58 engage the notches in the discs attached to the drums 28 with the result that the ribbons 30 and 39 are kept in the right position in relation to each other, so that their perforations coincide as nearly as possible. At the point where the negative film

ribbon passes the lighting device 31 it is supported by a bent piece 63 carried by the lever 64 (Fig. 1) which is mounted on the pivot 65 for swinging movement in a vertical plane.

5 Above the swinging or oscillating lever 64 another lever 66 is arranged, which rotates on the same pivot 65. This lever 66 has the form of a fork and is fitted with fingers 67 10 (Fig. 2), which serve to guide the positive ribbon 39.

Between the oscillating levers 64 and 66 a spring 21 is fitted, and the aforesaid levers are further connected with each other 15 by means of an adjustable pin 72 or the like which is subjected to the action of a spring 71.

The oscillating lever system 64, 66 is supported against the eccentric disc 18 by means 20 of a collar 69 and a hollow screw 68. The spring 70 arranged beneath the lower lever 64 pulls downwardly upon that lever, while the spring 71, which is immediately engaged with the pin 72 carried by the upper lever 25 66, presses down upon said lever 66, the latter exerting its pressure in turn through screw 68 against collar 69 which is thereby held against said eccentric. By withdrawing pin 72, lever 66 is disconnected from lever 64 and may be swung backwardly, thereby greatly facilitating the positioning 30 of the ribbons.

When the eccentric disc 18 is brought into a certain position the two oscillating levers 35 64 and 66 are lifted. Owing to the adjustable relation between the hollow screw 68 and the collar 69 and as the collar may move freely within said screw, the distance between the lever 66 and the lever 64 is sufficient 40 to avoid contact between the positive and negative ribbons. The latter which rests on the bent part 63 of lever 64 is lifted a bit from the plate 73 in the lighting device. Said plate—or the cover of the optical condenser 32 is fitted with pointed pins 45 74 which are adapted to engage the perforations in the ribbons 30 and 39. In the position of the levers 64 and 66 referred to the ribbons 30 and 39 are drawn forward and 50 the drums 28 are fastened in a certain position by means of the arms 58. When the surfaces of the pictures on both ribbons have been brought to suit each other exactly, the lifting levers 64 and 66 move 55 downwards, with the result that both ribbons are pushed in on the pins 74. The bent piece 63 on oscillating lever 64 is then situated below the surface of the glass-plate 73 of the lighting device, so that the negative 60 ribbon is pressed against the glass-plate 73.

When the oscillating levers 64 and 66 are lifted, the slack in the two ribbons 30 and 65 39 is taken up and said ribbons are tightened, whereas the ribbons slacken little by

little during the downward motion of the levers. Hence, when the ribbons are engaged with the pins 74, there is no danger of their being damaged by rubbing against each other, because a certain amount of dis- 76 placement of the ribbons is possible.

As soon as the ribbons 30 and 39 are pressed between the glass-plates 73 and 75, the exposure opening in the disc 35 passes the electric lamp and the light falls on the 75 ribbons. After exposure both levers 64 and 66 are again lifted by means of the eccentric disc 18 and the ribbons are loosened from the pins 74 and withdrawn from each other so far that they may be shifted independently of each other. After a new step 80 the ribbons are again pressed in between the glass-plates, lighted, and so on.

During the oscillating motion the levers 64 and 66 are guided by the forks 77 and 78 85 on the rod 76, which is fixed to the frame of the machine.

I claim as my invention:—

1. Apparatus for the production of colored cinematographic films, comprising a 90 source of light for tri-color exposures; mechanism for repeatedly feeding positive and negative film ribbons through the apparatus and across the light source in such a manner that they occupy a superposed relation while passing across said light source; said mechanism including feeding means individual to each ribbon, and means for arresting the ribbon feed and pressing said ribbons together during such passage so as 95 to print the negative pictures on the positive ribbon; said feeding means acting to move the ribbons step by step in such a way that at each passage of the ribbons through the apparatus, part-pictures of a different 100 color are printed from the negative ribbon on the positive ribbon.

2. Apparatus for the production of colored cinematographic films, comprising a source of light; and means for feeding positive and negative film ribbons through the apparatus and relatively to the light source; said feeding means including a pair of guide drums for the negative ribbon disposed at each side of the light source, gearing for intermittently rotating one drum of each pair, means for continuously rotating the other drum of each pair at a lower speed than the first drum, and a pair of guide drums for the positive ribbon likewise disposed at 110 each side of the light source, the second-named pairs of drums being driven from the adjacent first-named pairs at a speed 115 which is a predetermined fraction of that of said first-named pairs.

3. Apparatus for the production of colored cinematographic films, comprising a source of light; spaced guide drums for feeding positive and negative film ribbons through the apparatus and across the light source; 130

a cover for said light source having pins for engagement with said ribbons for holding the same in superposed relation; a lever system for controlling the engagement and disengagement of the ribbons with and from said pins; notched centering discs connected with certain of said drums to turn therewith; a rock shaft; driving means therefor; and arms carried by said shaft for engagement with the notches in said discs to center the ribbons for engagement by the holding pins.

4. Apparatus for the production of colored cinematographic films according to the tri-color system, comprising a source of light for tri-color exposures; mechanism for repeatedly feeding through the apparatus and across the light source positive and negative film ribbons having the sensitive emulsions applied to one side only thereof, said mechanism including feeding means individual to each ribbon; and means for periodically arresting the ribbon feed and pressing the ribbons together as they pass the light source, so as to print the negative pictures on the positive film; said feeding means acting to move the ribbons forward step by step in such a way that the steps occur in the same period of time but at a speed such that each step of the negative ribbon is three times as long as that of the positive ribbon, whereby at each passage of the ribbons through the apparatus part-pictures of a different color are printed from the negative ribbon on the positive ribbon.

5. Apparatus for the production of colored cinematographic films, comprising a source of light; means for feeding positive and negative film ribbons through the apparatus and across the light source; a cover for the light source having stationary retaining devices for engagement with said ribbons to hold them in superposed relation during exposure; and a lever system for controlling the movement of the ribbons into and out of engagement with the retaining devices.

6. Apparatus for the production of colored cinematographic films, comprising a source of light; means for feeding positive and negative film ribbons through the apparatus and across the light source; a cover for the light source having retaining devices thereon for engagement with said ribbons to hold them in superposed relation during exposure; and a lever system for pressing the ribbons into superposed engagement with the retaining devices and thereafter lifting them out of such engagement.

60 7. Apparatus for the production of colored cinematographic films, comprising a source of light; means for intermittently feeding positive and negative film ribbons through the apparatus and across the light source; a cover for the light source having

retaining devices for engagement with said ribbons to hold them in superposed relation during exposure; a lever system for controlling the engagement and disengagement of the ribbons with and from the retaining devices; and means operatively associated with said feeding means for centering the ribbons for such engagement at the end of each intermittent feeding movement.

8. Apparatus for the production of colored cinematographic films, comprising a source of light; means for feeding positive and negative film ribbons through the apparatus and across the light source; a cover for the light source, having retaining devices for engagement with said ribbons to hold them in superposed relation during exposure; a lever system for controlling the engagement and disengagement of the ribbons with and from the retaining devices; notched centering disks operatively connected with said feeding means to move therewith; and means engageable in the notches of said disks to center the ribbons for engagement with said retaining devices.

9. Apparatus for the production of colored cinematographic films, comprising a source of light; spaced guide drums for feeding positive and negative film ribbons through the apparatus and across the light source; a cover for said light source having retaining devices for engagement with said ribbons to hold them in superposed relation during exposure; a lever system arranged between said drums for controlling the engagement and disengagement of the ribbons with and from the retaining devices; and means for centering the ribbons for such engagement, said centering means including elements immediately connected to certain of said drums to turn therewith.

10. Apparatus for the production of colored cinematographic films, comprising a source of light; spaced guide drums for feeding positive and negative film ribbons through the apparatus and across the light source; a cover for said light source having retaining devices for engagement with said ribbons to hold them in superposed relation during exposure; a lever system arranged between said drums for controlling the engagement and disengagement of the ribbons with and from the retaining devices; and means for centering the ribbons for such engagement, said centering means including notched disks connected with certain of said drums to turn therewith, and arms movable into and out of engagement with the notches in the disks.

11. Apparatus for the production of colored cinematographic films, comprising a source of light; means for feeding positive and negative film ribbons through the apparatus and across the light source; a cover for the light source having retaining devices

for engagement with said ribbons to hold them in superposed relation during exposure; a lever system for controlling the engagement and disengagement of the ribbons with and from the retaining devices; notched centering disks associated with said feeding means for operation thereby; a rock shaft; driving means for the rock shaft; and arms carried by said shaft for engagement with the notches in said disks to center the rib-

bons for engagement with said retaining devices.

In testimony that I claim the foregoing as my invention, I have signed my name in presence of two subscribing witnesses.
